UNITED STATES PATENT OFFICE.

JULIUS THEODOR OTTO ORTLOFF, OF HEIDELBERG, GERMANY.

BOOK-STAPLING MACHINE.

SPECIFICATION forming part of Letters Patent No. 512,741, dated January 16, 1894.

Application filed August 12, 1893. Serial No. 483,042. (No model.) Patented in Germany July 4, 1891, No. 63,254, and in France November 12, 1891, No. 217,393.

To all whom it may concern:

Be it known that I, JULIUS THEODOR OTTO ORTLOFF, a subject of the Grand Duke of Baden, and a resident of Heidelberg, in the Grand 5 Duchy of Baden, Empire of Germany, have invented certain new and useful Improvements in Book-Stapling Machines, with a device for putting the sheets on and off, (for which patents have been obtained in Germany, No. 10 63,254, dated July 4, 1891, and in France, No. 217,393, dated November 12, 1891,) of which the following is an exact specification.

My invention relates to a book-stapling machine, which is provided with a device for 15 putting the sheets on and off and constructed in such a manner that the sheets are first stapled and then folded. By this arrangement the efficiency of my machine is much greater than is the case in stapling-machines with a 20 separated folding-machine, because in my machine simultaneously one sheet is stapled and another folded. This result is attained by the arrangement of feeding-rollers, serving for conducting the sheets to the stapling mechanism, and of folding-rollers, by which the sheets, 25 after having been stapled, are folded together. The latter circumstance is highly important for sheets, which must be quickly folded, such as newspapers, pamphlets and so on.

30 In order to make my invention more clear, I refer to the accompanying drawings, in which similar letters denote similar parts throughout the different views and in which—

Figure 1 is a side-view. Fig. 2 is a front view of my improved machine. Fig. 3 shows the heads for forming the staples in two different positions.

In carrying my invention into effect, I construct my machine in the following manner:

40 Z is the frame of the machine having at its upper end a crank shaft A supported by suitable bearings and driven by a pulley P. At the free end of the crank shaft A there is secured a crank lever L attached to the slide K', which, together with the head K, is guided in the guide-pieces O' O² of arm O, the latter forming part of frame Z. The staples are formed in the head K. Opposite to this latter, there are arranged between the guide-

pieces N' N² fixed to the arm N of frame Z, the anvil U and the slide U', which latter is likewise fixed at a crank lever M and moved by a crank shaft B from a pulley E⁴ connected with the pulley E³ of the crank shaft A by means of the belt C². The head U serves for bending the staples and for holding the paper during the stapling process. The head K and the anvil U are connected with the slides K' and U' respectively by angular pieces Q and 55 T pivoted at the arms O and N of the frame Z and having slots a b and c d, in which the pins e f and g h attached to the heads K and U are sliding.

X X' are two upright arms of the frame of 60 which X supports two feeding rollers W W' serving for leading the sheets of paper from the table T' to the stapling device by means of the endless band Y guided over the roller W and the folding roller F. The rollers W 65 W' are rotated from the pulley E² connected with the pulley E' on shaft A by the endless band C'.

The double armed lever V pivoted in the center of folding roller F is operated by the 70 cam-shaped roller F' and serves for raising the sheets a little before being folded.

G G' is a double-armed folding-lever pivoted to the arm O and provided with the folding knife J. This lever G G' is actuated by 75 the cam G².

V' is a stop for securing the position of the sheets to be folded.

The manner of operation of the machine is as follows: The sheets are put from the table 80 T' between the feeding rollers W W' and conveyed to the anvil U and head K by the endless band Y. By the movements of the head K and anvil U, as shown in Fig. 3 of the drawings, the sheets are stapled and then led 85 to the folding rollers F F'. Here the folding knife J presses the sheets between the rollers F and F' and thereby folds them together in the manner illustrated by Fig. 1.

I do not confine myself to the exact form 90 of construction shown in the drawings, as I may arrange of course more than two folding rollers before or behind the stapling device and employ several anvils U and heads K. Therefore,

What I desire to secure by Letters Patent of the United States is—

1. In a book-stapling machine, the combination with the stapling device proper of feed rollers W W', arranged one above the other, delivery rollers F F' arranged one in front of the other, and transporting bands Y running over the rollers W and F and between head K and anvil U of the stapling device, a folding-knife I secured to arm G being arranged above the space between the delivery rollers, for the purpose as described.

2. In a book stapling machine, the combination with the staple-forming-head K and the staple-bending-anvil U, held and moved by slides K' and U' respectively, of feed-rollers W W' arranged one above the other, delivery-rollers F F' arranged one in front of the other, transporting bands Y running over the rollers W

and F and between head K and anvil U, the latter two being connected with the slides K' and U' by levers Q and T having slots a b and c d, pins e h fixed to the head and anvil taking into the slots a and d respectively, and pins f g fixed to the slides taking into the slots b and c respectively; a folding knife I secured to double-armed levers G G' being arranged above the space between the delivery rollers, said lever being actuated by cam G² on the main shaft A, for the purpose as described.

In testimony whereof I have signed this specification in the presence of two subscribing witnesses.

JULIUS THEODOR OTTO ORTLOFF.
